US00D792393S

(12) **United States Design Patent** (10) **Patent No.:** **US D792,393 S**
(45) **Date of Patent:** **** Jul. 18, 2017**

(54) **PORTABLE DISPLAY DEVICE WITH COVER**(71) Applicant: **Apple Inc.**, Cupertino, CA (US)(72) Inventors: **Jody Akana**, San Francisco, CA (US); **Bartley K. Andre**, Palo Alto, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Shin Nishibori**, Kailua, HI (US); **Matthew Dean Rohrbach**, San Francisco, CA (US); **Peter Russell-Clarke**, San Francisco, CA (US); **Christopher J. Stringer**, Woodside, CA (US); **Eugene Antony Whang**, San Francisco, CA (US); **Rico Zörkendorfer**, San Francisco, CA (US)(73) Assignee: **Apple Inc.**, Cupertino, CA (US)(***) Term: **14 Years**(21) Appl. No.: **29/484,753**(22) Filed: **Mar. 12, 2014****Related U.S. Application Data**

(63) Continuation of application No. 29/437,767, filed on Nov. 20, 2012, now Pat. No. Des. 704,702, and a continuation of application No. 29/437,776, filed on Nov. 20, 2012, now Pat. No. Des. 701,205, said application No. 29/437,767 is a continuation of application No. 29/386,263, filed on Feb. 25, 2011, now Pat. No. Des. 671,114, said application No. 29/437,776 is a continuation of application No. 29/386,263.
